Primary Examiner — Cynthia Ramirez(74) *Attorney, Agent, or Firm* — Luedeka Neely Group PC(57) **CLAIM**

The ornamental design for a winch control housing, as shown and described.

DESCRIPTION

FIG. 1 is a front perspective view of a winch control housing showing our new design;

FIG. 2 is a rear perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines show portions of the winch control housing which form no part of the claimed design.

1 Claim, 8 Drawing Sheets(56)
